UNITED STATES PATENT OFFICE.

DANIEL E. WHITFIELD, OF MALVERN, IOWA.

LOADING DEVICE.

No. 908,054.

Specification of Letters Patent.

Patented Dec. 29, 1908.

Application filed May 28, 1908. Serial No. 435,473.

To all whom it may concern:

Be it known that I, DANIEL E. WHITFIELD, a citizen of the United States, residing at Malvern, in the county of Mills and State of Iowa, have invented certain new and useful Improvements in Loading Devices; and I do declare the following to be a full, clear, and exact description of the invention, such as will enable others skilled in the art to which it appertains, to make and use the same.

My invention relates to certain improvements in what may be termed "loading devices," particularly adapted for use in connection with what may be styled "slip" scrapers.

Said invention has for its object to provide for the ready, expeditious and effective loading of vehicles or wagons as in disposing of accumulated matter, such as dirt, and the like; also, to provide for the carrying out of all of said objects in a cheap and simple manner.

With these and other objects in view, the invention consists of certain novel features of construction, combination and arrangement of parts as will be described and particularly pointed out in the appended claims.

In the accompanying drawing, illustrating the preferred embodiment of my invention, Figure 1 is a plan view thereof; Fig. 2 is a sectional elevation of the same, with the horizontal frame section shown in dotted lines in the position it assumes in effecting the dumping operation, also with a car attached thereto; Fig. 3 is a longitudinal sectional view of the main portion of the device, the base portion thereof being omitted; and Fig. 4 is a broken detail perspective view of the hinged frame section showing more particularly its adjunctive parts, including its retaining latch and the like. Fig. 5 is a vertical transverse section produced through the "pit" inclosure.

In practicing my invention, I provide a suitable base frame, 1, and an upright frame, 2, suitably assembled in position therewith and upon these are mounted the operative devices of the invention. A member, 3, which may be termed the "pit inclosure," is arranged at the base of an upwardly inclined member, 4, of the frame, 2, said inclosure having suitably arranged therewith inclined boards or ways, 5, up which is drawn the slip scraper, as in discharging its contents into said pit inclosure preliminary to the reception of said contents by the car, 6, more fully

described later. Said inclined boards or ways, 5, are suitably held in position in connection with said pit inclosure, 3, by dependent cross pieces, 7, suitably adapted for engagement laterally with the inclosure, 3. The under side of the boards or ways, 5, have preferably secured thereto cross pieces, 8, for reinforcing the same or aiding the holding together of its constituent parts when made of several pieces. The inclosure 3 has arranged across its upper edge transverse bars, 9, also preferably a rod, 10, said bars aiding in holding the slip scraper in proper position when disposing of its contents, as above noted, and said rod or bar serves to strengthen the parts at that point.

The car, 6, which is of suitable construction is equipped with suitable rolls, 11, upon its bottom, and rolls, 12, laterally in its sides, the former rolls engaging with ways or rails upon the inner sides of the inclined members, 4, of the frame, 2, and the latter rolls engaging the upright portions of said member, 4, to suitably reduce friction, as will be readily understood. Both the corners of said car, as also the upper corners of the member 4, of the inclined frame, 2, are armed with right-angled castings, 13 and 14, respectively, for additional reinforcing or strengthening of said parts.

The car, 6, has secured to its bottom, about centrally thereof, a keeper-like member, 15, and centrally to said keeper is secured a hoisting rope, 16, passing intermediate of parallel bars, 17, secured to a hinged section, 18, of said inclined member, 4, under a cross bar, 19, secured transversely of the upper surface of said parallel bars. Said hoisting rope is passed downwardly and thence laterally in engagement with pulleys, 20, 21, two of which are applied to each side of the lateral members of the horizontal frame, 1, said hoisting rope thus being adapted to be connected to the doubletree or draft bar of the slip scraper team after the slip scraper has deposited its contents into the inclosure pit and the car, 6, for the subsequent convenient elevation of the car with its load for suitably dumping the same. Said car also has applied to its front edge latch bars, 22, for effecting the ready disengagement of the retaining latch of the hinged frame section, 18, as will presently be apparent.

The parallel bars 17 are provided just a short distance from the cross bar, 19, with oppositely extending arms, 19^a, for engage-

ment with the keeper, 15, when the car, 6, has been elevated upon the hinged frame section, 18, serving to hold said car in proper position upon said hinged frame section during the dumping operation, as will be noted from the dotted line showing thereof. Said cross bar, 19, would also have the same action in the event of the failure of the keeper member 15 to make engagement with the members, 19^a, thus providing an additional means for effecting that end.

The hinged frame section is pivoted or connected preferably to the upper part of the main portion of the inclined frame, 2, by means of a pintle or rod, 23, passing through the central bars, 17, and cleats, 24, secured to the bottom edges of the lateral bars of said inclined frame. The upper end of said hinged frame section has preferably secured thereto a right-angular plate or casting, 25, the purpose of which will presently appear.

A catch, 26, is suitably pivoted at its inner end to ears of a casting, 27, secured to the central upper cross bar of the inclined frame, 2, and has its effective portion stepped as at 28 for engagement with the upper end of the hinged frame section, 18, for the retention of the same in initial position. The extreme outer portion of said catch is rounded as at 29, with its outer terminal apertured to receive the otherwise free end of a preferred rod spring, 30, whose upper end is fixed in the upper cross bar of the inclined frame. Said spring is retained in operative position by means of a keeper, 31, or other suitable means secured to the upper cross bar of said inclined frame. Of course, any other form of spring or resilient means may be substituted in lieu of the rod spring herein shown, which will equally serve the purpose. The catch 26 has secured thereto, near its inner end, a cross plate, 26^a, having lateral flanges between which are received the outstanding portions of the right-angular plate, 25, of the hinged frame section, 18, for the retention of said catch in suitably adjusted position on said hinged frame section.

Weighted ropes or cables, 32, have their upper ends suitably secured to the upper cross bar member of the hinged frame section, 18, said cables being passed over pulleys, 34, suitably hung upon the lateral members of the inclined frame, said weighted cables serving to automatically return said hinged frame section, with the car after having been relieved of its contents, to position in the inclined frame, as in making its return trip down said frame to the pit inclosure, as will be readily understood.

In the operation of the device, the car is placed in the pit and after having received its load it is raised, by suitably applying the draft to the hoisting rope, 16, as above described, the keeper, 15, of said car, will, upon

reaching its final elevated position, engage the right-angular members, 19^a, and thus effect connection between said car and the hinged frame section, 18. The latch bars, 22, will engage the lateral flanges of the cross plate, 26^a, of the catch, 26, and thus disengage said catch from the hinged frame section, the continued strain upon the hoisting rope pulling down on the outer end of the hinge section thus effects the dumping of said hinged frame section with the car into the position indicated in dotted lines for the dumping of the contents of said car into a vehicle or wagon. It will be noted that at this juncture, the keeper member will effect, in connection with the bars, 19^a, of the hinged frame section, the retention of the car in position upon the latter when in dumped position and will be thus retained until said frame section, with the car, is returned to its initial position in the inclined frame. It will also be noted that the latch bars, 22, will have the effect of holding the catch out of engagement with the hinged frame section while being tilted and during the dumping of the car.

It will be noted that the lateral bars of the frame 1 may serve as runners, as will be observed, in transporting the machine from place to place, and that any of the various parts upon which wear is received may be armed with metal in any suitable way. Said bars may also be provided with keepers for the passage therethrough of suitable means for staking the frame in position.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim as new and desire to secure by Letters-Patent, is:

1. A device of the character described comprising a supporting frame having a pivoted or tilted section, said tilting section and said frame being connected together so as to permit of the disengagement of said frame section, a car traveling upon said supporting frame, said car having latch bars projecting from its forward edge and adapted to engage the means of connection between said tilting frame section and said supporting frame, and means for elevating said car.

2. In a device of the character described, a supporting frame having a hinged section, a spring catch applied to said supporting frame and adapted to engage said hinged frame section, a car traveling upon said supporting frame and equipped with latch

bars adapted to disengage said catch from said hinged frame section, and means for the actuation of said car.

3. A device of the character described, 5 comprising a supporting frame having a pivoted or tilting section, a spring catch applied to said supporting frame, said catch having a cross plate provided with lateral flanges, a car traveling upon said 10 supporting frame having latch bars adapted to engage said lateral flanges, and means for actuating said car.

4. A device of the character described comprising a supporting frame having lateral 15 ways upon its inner surface, said frame having a spring catch at its upper end, said catch having a flanged cross plate and said hinged frame section having a right-angular plate with its outstanding arm adapted to be received 20 between the flanges of the cross plate of said catch, a car adapted to travel upon said supporting frame and having latch bars adapted to engage the lateral flanges of said cross plate, and means for the actuation 25 of said car.

5. A device of the character described comprising a supporting frame having a tilting or pivoted section, means applied to said supporting frame adapted for the 30 retention of said pivoted section in the initial position, a car traveling upon said supporting frame equipped with latch bars effective for tripping the means of connection 35 between said tilting section and said supporting frame, said car having a keeper

member secured thereto upon its bottom and said pivoted or tilting frame section having right-angular members effective for engagement with said keeper, and means for the actuation of said car.

6. A device of the character described, 40 embracing a supporting frame having a tilting or pivoted section, means for effecting connection between said tilting frame section and said supporting frame, said 45 tilting or pivoted frame section having right-angular members secured about centrally thereto and a cross bar, said right-angular members being arranged adjacent to said cross bar, a car traveling upon said 50 supporting frame, and means for the actuation of said car, said car actuating means passing intermediate of bar members of said pivoted frame section and under said cross bar.

7. A device of the character described, 55 comprising a supporting frame having a pivoted or tilting section, means for effecting connection between said frame and said pivoted section, automatically - returning 60 means for said pivoted section, a car traveling upon said supporting frame, and means for actuating said car.

In testimony whereof I have hereunto set my hand in presence of two subscribing 65 witnesses.

DANIEL E. WHITFIELD.
